UNITED STATES PATENT OFFICE.

VICTOR GUINZBURG, OF NEW YORK, N. Y., ASSIGNOR TO I. B. KLEINERT RUBBER COMPANY, OF NEW YORK, N. Y., A CORPORATION OF NEW YORK.

FLOTATION DEVICE.

1,364,275.

Specification of Letters Patent.

Patented Jan. 4, 1921.

Application filed September 18, 1920. Serial No. 411,286.

To all whom it may concern:

Be it known that I, VICTOR GUINZBURG, a citizen of the United States, and a resident of the city, county, and State of New York, have invented a certain new and useful Improvement in Flotation Devices, of which the following is a specification.

This invention relates to a flotation or swimming device in the nature of an inflatable bag having means for securing it to the body and adapted to be used to support the body while in the water.

The object of this invention is to provide a device, which will be simple and economical in construction, which will be effective in operation and which can be worn without interfering with the movements of the body while swimming.

With these objects and other objects in view, I have devised the particular arrangement of parts hereinafter set forth and more particularly pointed out in the claims appended hereto.

Reference is to be had to the accompanying drawing forming a part hereof in which—

Figure 1 is a plan view of a flotation device made in accordance with my invention.

Fig. 2 is a transverse sectional view of the same on the line 2—2 of Fig. 1.

Fig. 3 is a sectional view on the line 3—3 of Fig. 1, looking in the direction of the arrows.

Fig. 4 is a sectional view of a portion of the inflatable bag showing the construction of the inflation valve.

Fig. 5 is a sectional view on the line 6—6 of Fig. 1 looking in the direction of the arrows.

Fig. 6 is a view showing the manner in which the device appears when in use.

Throughout the various views of the drawings, similar reference characters designate similar parts. In the preferred embodiment of my invention as disclosed in the accompanying drawing, 1 indicates an inflatable bag which is substantially rectangular in shape and may be made by transversely folding a square section of material and securing the edges together. The edges of

the bag 1 are secured together by stitching 2 and are additionally reinforced by means of a binding strip 3 which incloses the edges and is cemented thereover. The manner in which the device is manufactured forms the subject matter of a separate application for

patent, said application being Serial No. 411,285, filed Sept. 18, 1920.

At 4 is the inflation valve which consists of a collapsible or flexible rubber tube 5 which lies between the folds of the bag and extends substantially co-extensive with the outer or free edge 6 of the bag. This tube 5 is cemented or otherwise secured to the bag 1 and secured within the tube 5 is a threaded sleeve 6^a. The sleeve 6 projects outside of the bag and is adapted to receive a closure cap 7 to prevent the escape of air from the interior of the bag.

It will be seen that the bag may be inflated by means of air blown through the sleeve 6^a and through the flexible or collapsible tube 5. To prevent the escape of air while the cap 7 is being placed in position, the flexible or collapsible tube 5 may be squeezed or pressed together as indicated by the dotted lines in Fig. 4.

At 8 are the tapes which are utilized to secure the device about the body of the user. These tapes are attached to the bag 1 through the medium of triangular tabs 9. These tabs each consist of a triangulated strip of material folded upon itself with the tapes 8 lying between the folded portions and cemented therein.

If desired however, the tabs 9 may comprise two sections of material adhesively secured together with the ends of the tapes 8 secured between them.

It will be seen that the two sections of each tab embrace a portion of the bag between them and are secured to the bag 1 and are pendant from two of its corners. It will also be noted that the ends of the tapes 8 extend over the portion of the bag at the corners which is covered by portions of the tabs 9. This particular construction affords a strong and substantial method of attaching the tapes in position without the necessity for stitching them in place or otherwise perforating the inflatable bag.

In addition, the arrangement of the tabs forms a substantial joint at the corners of the bag and aids in preventing leakage of air at those points.

In Fig. 6, the manner in which the device is used is disclosed. The bag is secured about the body by means of the tapes 8 and the bag 1 is freely pivotal in any direction that it may be moved by the pressure of the water. The position in which the device

is used enables it to be worn without in any way interfering with the movements of the wearer. The device is preferably made of a rubberized, air and waterproof material, 5 enabling it to be inflated and retain the air indefinitely. Usually, devices of this character are made of a material which will not retain the air until they are moistened by the water and they cannot be inflated while 10 they are dry. In applicant's construction, however, a material is preferably used which will enable the device to be inflated regardless of whether it is moistened or not. Such a material may be thin rubber 15 sheeting, rubberized silk or any material of like character.

From the foregoing, it is obvious that my invention is not to be restricted to the exact embodiment shown but is broad enough 20 to cover all structures coming within the scope of the annexed claims.

What I claim is:—

1. A device of the class described comprising an inflatable body, tabs extending 25 from the securing edge of said body and securing tapes held within said tabs.
2. A device of the class described comprising an inflatable body, tabs pendant therefrom, securing tapes held within the 30 tabs and overlying the inflatable body.
3. A device of the class described com-

prising a substantially rectangular inflatable body, a pair of tabs, each of which consists of a strip of fabric folded upon itself and secured to said body, and tying tapes 35 having their ends lying between the folds of the tabs and secured therein.

4. A device of the class described comprising an inflatable body having a securing tape, a tab secured to and projecting from 40 said body, said tab comprising a triangulated strip of material folded upon itself with a portion of the inflatable bag lying between and secured to the folded portions of said tab, said tape having one of its ends 45 secured between the folded portions of said tab.

5. A device of the class described comprising an inflatable bag, securing tapes projecting from two corners thereof and an 50 inflation valve lying co-extensive with the outer edge of said bag with its end projecting outside of said bag.

6. A device of the class described comprising an inflatable bag having a securing 55 tape, a tab in which said tape is held, said tab comprising two layers of material between which a portion of the inflatable bag and one end of the tape is secured.

Signed at the city, county and State of 60
New York this 16th day of September, 1920.

VICTOR GUINZBURG.
